UNITED STATES PATENT OFFICE.

REINHOLD BURGER, OF BERLIN, GERMANY, ASSIGNOR TO AMERICAN THERMOS. BOTTLE COMPANY, OF NEW YORK, N. Y., A CORPORATION OF MAINE.

DESIGN FOR A BOTTLE.

No. 38,834.

Specification for Design.

Patented Sept. 24, 1907.

Application filed August 10, 1907. Serial No. 388,066. Term of patent 14 years.

To all whom it may concern:

Be it known that I, REINHOLD BURGER, a subject of the German Empire, and a resident of Berlin, Germany, have invented a new, original, and ornamental Design for a Bottle, of which the following is a specification, reference being had to the accompanying drawing, forming part thereof.

My new, original and ornamental design for a bottle is shown in the accompanying drawing, in which

Figure 1 is a top plan view of a bottle, and Fig. 2 is a side elevation of the same.

I claim:

The ornamental design for a bottle, as shown.

REINHOLD BURGER.
